UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

ELECTRIC CLOCK.

1,228,819.

Specification of Letters Patent.

Patented June 5, 1917.

Application filed October 26, 1916. Serial No. 127,771.

To all whom it may concern:

Be it known that I, WILSON E. PORTER, a citizen of the United States, residing at New Haven, in the county of New Haven and 5 State of Connecticut, have invented a new and useful Improvement in Electric Clocks; and I do hereby declare the following, when taken in connection with the accompanying drawings and the characters of reference 10 marked thereon, to be a full, clear, and exact description of the same, and which said drawings constitute part of this application, and represent, in—

Figure 1 a view in front elevation of an 15 electric-clock constructed in accordance with my invention.

Fig. 2 a view thereof in side elevation.

Fig. 3 a view on an enlarged scale of the 20 clock-case shown in horizontal section on the line 3—3 of Fig. 1, with the clock-mechanism shown in plan.

Fig. 4 a view in vertical section on the 25 line 4—4 of Fig. 3.

Fig. 5 a view in vertical section on the line 5—5 of Fig. 3.

My invention relates to an improvement 30 in electric-clocks primarily designed for use as automobile clocks, but not so limited, the object being to produce, at a low cost for manufacture, a simple, compact, and reliable electric clock constructed with particular reference to a self-cleaning contact-mechanism.

With these ends in view, my invention 35 consists in an electric-clock having certain details of construction as will be herein-after described and pointed out in the claims.

In carrying out my invention as herein shown, I employ a pair of electro-magnets 40 6 secured to a bracket 7 attached by screws 8 to the inner face of a rear disk-shaped frame-plate 9 which is connected by pillars 10 to a corresponding front frame-plate 11.

Above the electro-magnets 6, I locate a 45 pivotal armature 12 mounted upon a rock-shaft 13 the ends of which are journaled in the frame-plates 9 and 11 aforesaid. At its opposite end, the armature 12 is provided with an operating-finger 14 the upper face 50 of which coacts with the forwardly turned arm 15 of a trigger 16 rocking upon a stud 17 in the rear frame-plate 9. A pin 18 in the said trigger 16 is engaged by a trigger-spring 19 which is fastened to the plate 9 55 and which exerts a constant effort to swing

the trigger inward. The trigger 16 is formed upon its lower edge with a cocking-shoulder 20 co-acting with a cocking-pin 21 mounted in the disk-shaped body 22 of a circuit-closer having an integral contact-arm 23.

The lower face of the operating-finger 14 of the armature 12, co-acts with the upper face of an operating-pin 24 mounted in the disk-shaped body 22 of the circuit-closer which rocks upon a stud 25 in the frame-plate 9. A pin 26 in the said body 22 is engaged by a spring 27 which exerts a constant effort to swing the contact-arm 23 of the circuit-closed outward into its circuit-closing position. The beveled outer end 70 of the said arm 23 makes sliding contact with a contact-spring 28 secured to a stud 29 mounted in the frame-plate 9 but insulated therefrom by fiber washers 30 and connected by a wire 31 to one of the two electro-magnets 6. An adjustable stop-arm 32 of insulating material, mounted upon a stud 33 in the frame-plate 9 limits the swinging movement of the said arm 23 in the direction of closing the circuit.

Mounted upon the armature-shaft 13 aforesaid, is a bowed driving-arm 34 the lower end of which carries a spring-pawl 35 engaging with a driving ratchet-wheel 36 mounted upon an arbor 37 also carrying a 85 driving gear-wheel 38 which meshes into a driving-pinion 39 upon the arbor 40 of the third wheel 41 of the time-train which may be of any suitable construction and arrangement and which does not need detailed description more than to say that the said third-wheel arbor 40 mounts a pinion 42 90 meshing into the center-wheel 43 of the time-train.

The time-train, however constructed, is 95 driven by means of a periodically energized helical driving-spring 44 one end of which is attached to the driving-arm 34, and the other end of which is attached to a pin 45 in the rear movement-plate 46 of the clock-movement, the said plate 46 being secured by pillars 47 to the front movement-plate 48 which in turn is secured to the inner face of the front frame-plate 11. A stop-screw 49 threaded into one of the pillars 10 and 100 105 provided with a lock-nut 50, is provided for limiting the outward swing of the armature 12 away from the magnets 6.

As herein shown, the right-hand electro-magnet 6, is connected to a wire 51 which 110

leads to a plug 52 mounted in the frame-plate 9 and insulated therefrom by a bushing 53 of insulating material. The said plug 52 is adapted to enter a socket 54 formed upon the inner end of a binding-post 55 mounted in the back 56 of the clock-case 57, the post 55 being insulated from the back 56 by means of a bushing 58 of insulating material. The other binding post 59 is also mounted in the back 56 to which, however, it is grounded.

The rear frame-plate 9 is connected by pillars 60 to the back 56 of the clock-case 57 the forward edge of which is provided with an annular fastening-flange 61 having screw-holes 62 by means of which the clock-case is secured in place in the cowl or instrument-board of the automobile. The forward end of the case 57 is exteriorly threaded for the application of a knurled bezel 63 carrying a glass 64 and a mat 65 which latter rests upon the dial 66.

Having now described the mechanism of my improved electric clock, I will proceed to set forth the mode of its operation. For this purpose it may be assumed that the time-train is running, which is the condition in which the parts are shown in all of the drawings. At this time the tension of the driving-spring 44 is exerting its power through the pawl 35, to turn the ratchet-wheel 36 and hence the driving-gear-wheel 38 which in turn drives the driving-pinion 39 mounted on the arbor 40 of the third wheel 41 of the time-train. The time-train is thus driven through the third-wheel arbor 40. As the ratchet-wheel 36 turns under the tension of the spring 44, the driving-arm 34 with which the said spring is connected, is gradually drawn inward with the effect of rocking the shaft 13 and correspondingly swinging the armature 12 outward, whereby the same is lifted above the cover of the electro-magnets 6. This outward swinging or lifting movement of the armature is a gradual movement and corresponds to the slow turning of the ratchet-wheel 36 under the tension of the spring 44. As the armature gradually moves outward, its operating-finger 14 pushes against the operating-arm 15 of the trigger 16 which is thus slowly lifted against the tension of the trigger-spring 19. In this manner, the shoulder 25 of the trigger 16 is gradually lifted and disengaged from the pin 21 mounted in the body 22 of the circuit-closer. At the instant the said shoulder 25 is in this manner fully cleared from the pin 21, the spring 27 of the circuit-closer asserts itself to rock the same upon its stud 25, whereby its contact-arm 23 is smartly moved outward, making a "wiping" or sliding contact with the spring 28 and stopping against the stop-arm 32. The circuit is thus momentarily closed through the electro-magnets 6 with the effect of attract-

ing the armature 12 and swinging the driving-arm 34 outward with the result of re-energizing the driving-spring 44 and causing the driving-pawl 35 to "ratchet-back" and take up one tooth of the ratchet-wheel 36 to which the power of the spring 44 is continuously applied except at the moment of "ratcheting back" as described. The re-energization of the driving-spring 44 will be effected about every thirty seconds, though this interval may be varied as desired in the initial construction of the mechanism. When the armature 12 is attracted by the magnets 6 as aforesaid, its finger 14 strikes a smart blow upon the pin 24 in the disk 22 of the circuit-closer and turns the same from left to right, whereby the contact-arm 23 is disengaged from the contact-spring 28 and the circuit abruptly broken. At the same time, the pin 21 in the disk 22 moves from right to left into position to clear the shoulder 25 of the trigger 16 which is then swung downward by the trigger-spring 19 into the position shown in Fig. 5, whereby the circuit-closer is cocked by the said pin and shoulder in its open-circuit position.

Supposing the current to enter through the binding-post 55, it flows through the socket 54, plug 52, wire 51, through the coils of the electro-magnets 6 and out through the wire 31 to the insulated stud 29 and contact-spring 28. Then when the contact-arm 23 makes contact with the spring 28, the current grounds through the parts of the clock-mechanism and case and passes out through the binding-post 59.

By employing, in an electric clock, a trigger-mechanism for cocking the contact-arm in its full open position, I am enabled to close the circuit suddenly, whereby I secure greater reliability of performance than can be had with a mechanism constructed to effect a gradual approach of the contact points. Furthermore, by utilizing the travel of the armature as a means of gaining time, I am able to prolong the contact into a sliding or "wiping" contact which keeps the contact points clean. In other words, when the armature is moving from its open to its closed position, the contact-arm is wiping the contact-spring and moving through a predetermined distance. Therefore, there can be no such thing, in my improved construction, as an opening of the circuit before the contact-arm has had an opportunity of wiping over the contact-spring. The gap between the operating-finger 14 of the armature 12 and the pin 24 carried by the circuit-closer, is initially spaced so that the contact-arm 23 will have time to travel over the contact-spring 28 and be stopped by the stop-arm 32 before the operating-finger 14 of the armature strikes the pin 24 of the circuit-closer for turning the same smartly into its open-circuit position.

I claim:-

1. In an electric clock, the combination with an electro-magnet, of an armature therefor, a trigger operated by the said armature; a circuit-closer cocked and released by the said trigger and operated for opening the circuit by the said armature, a contact with which the circuit-closer co-acts, and a driving-spring energized by the movement of the armature and connected with the time-train of the clock.

2. In an electric clock, the combination with an electro-magnet, of a pivotal armature therefor, a trigger operated by the said armature, a circuit-closer cocked and released by the said trigger and moved by the said armature into its open-circuit position, a contact-spring with which the said circuit-closer has sliding contact, and a driving-spring periodically energized by the movement of the armature and connected with the time-train of the clock, the said armature when attracted by the said magnet operating the circuit-closer by a sharp blow so as to suddenly break its contact with the said spring and permit the trigger to cock it in its open-circuit position.

3. In an electric clock, the combination with an electro-magnet, of a pivotal armature therefor, a trigger operated by the said

armature, a circuit-closer cocked in its open-circuit position by the said trigger when moved into its open-circuit position by the said armature, a driving-arm connected with the armature, a driving-spring connected with the said arm and placed under tension thereby, and a time-train driven by the said arm under the power of the said spring.

4. In an electric clock, the combination with an electro-magnet, a pivotal armature therefor, a trigger having a cocking-shoulder and an operating-arm which latter co-acts with the armature, an oscillating circuit-closer cocked by the said cocking shoulder of the trigger when moved into its open-circuit position by the said armature, and provided with a contact-arm, a contact-spring with which the said contact-arm makes sliding contact, a driving-spring, and connection between the said driving-spring and the armature, whereby the spring is energized by the armature every time the same is moved by the energization of the magnet.

In testimony whereof, I have signed this specification in the presence of two subscribing witnesses.
